SPRING ASSEMBLING MACHINE

Jonathan A. Dickey, Memphis, Tenn.

Application July 5, 1940, Serial No. 344,064

16 Claims. (CL. 140—3)

This invention relates to machines for assembling and connecting spring coils employed in the manufacture of spring assemblies of units for beds, cushions, mattresses and the like.

In a known type of spring assembly, spiral hour glass coils are disposed in upright position in longitudinal and transverse rows with the individual coils in upright position, the longitudinal rows being spaced apart and the transverse rows being disposed in such relation that the edges of the top and bottom heads of the coils abut, or overlie in abutting relation, the top and bottom heads respectively of the adjacent coils. These abutting edges are tied together by continuous wire helicals which extend across the spring assembly and are threaded around the abutting edges of the coil heads.

The coils used have been of two slightly differing types, one of these having circular top and bottom convolutions, and the other having outwardly crimped and straight abutting portions on opposite sides of these coils, which permit the use of a smaller diameter helical and effect a more stable connection of the coils.

The helicals are threaded through either by hand or by machine. Hand threading is slow and laborious, the helicals being formed, cut to length and rotated into place by hand, but it is readily possible to use the crimped edge coils and by hand adjustment effect proper alinement and positioning of these portions, to permit threading through of the helicals. Even so, however, full advantage cannot be taken of the desired reduction in helical diameter except at the expense of undue slowing down of the work.

Machine threading is much more rapid and is at present very generally practiced. These machines line up coils, usually placed by hand, and thread through the coil joining helicals mechanically and with great rapidity, the helicals often being formed and threaded into place in the same operation and then automatically cut the helicals off as threading is completed, and many of the features of these machines are here employed.

Difficulty has however been had in properly positioning the abutting coil heads and so far as is known it has not been found feasible to position overlying or edge abutting positions of crimped edge coils and successfully mechanically thread helicals through, and the successful machines have been obliged to fall back on the circular top and bottom coils and make use of the loosely contacted joints by them affected.

The objects of this invention are:

To provide means for alining and positioning

abutting edges of spring coils in definite relation to facilitate the threading therearound of a joining helical.

To provide means for alining and positioning 5 rows of head abutting coils.

To provide means for advancing rows of coils which is adapted to facilitate the placing of successive rows of the coils.

To provide means for contacting overlapping 10 and abutting head portions of coils to permit threading of helicals therearound.

To provide means for releasing each helically joined row of coil edge portions to permit movement thereof away from joining position and 15 shifting of the next successive row into position for threading.

To provide means for cutting off each helical as threading is completed therefor and so timing such cut-off as to insure completion of threading prior to cut-off.

To provide means for coordinating the shifting of the coils, threading of the helicals, and shifting 20 of the coils thereafter.

To provide means for coordinating the advancement and stopping of the coils, the threading 25 of the helicals around the coil edges and the cut-off of the helicals.

To provide means for coordinating the forming, threading, stopping and cut-off of the helicals, with the stoppage or the dwell portion of 30 the coil movement, and the stoppage of forming of the helical during movement of the coils.

The means by which the foregoing and other 35 objects are accomplished and the manner of their accomplishment will readily be understood from the following specification upon reference to the accompanying drawings, in which:

Fig. 1 is an end elevation of the machine showing 40 five only of the longitudinal rows of coils, the machine being partially broken away to avoid duplication of the usual nine or more rows employed.

Fig. 2 is a sectional side elevation of the machine taken as on the line II—II of Fig. 1 showing 45 the timing cam and related actuated switches.

Fig. 3 is an end elevation of the opposite or drive side of the machine.

Fig. 4 is a longitudinal sectional elevation taken 50 as on the line IV—IV of Fig. 1 and looking in the same direction as Fig. 3.

Fig. 5 is a fragmentary sectional plan taken as on the line V—V of Fig. 4, showing the coil conveyor lineups.

Fig. 6 is an enlarged fragmentary plan, taken 55 on the same line as Fig. 5, showing links of one

pair of coil conveyors with the guides and supporting plates therefor and a portion of the helical channel.

Fig. 7 is a side view of the same conveyor with a portion of one link shown in section on the line VII—VII of Fig. 6.

Fig. 8 is a sectional plan showing fragmentary portions of two of the conveyors with coils in place and a fragmentary view of the helical feed-in and cut-off mechanism, the view being on the same scale as Figs. 6 and 7.

Fig. 9 is a sectional elevation taken on the line IX—IX of Fig. 8.

Fig. 10 is a longitudinal sectional elevation taken as on the line X—X of Figs. 8 and 9.

Fig. 11 is a fragmentary section taken on the same line as Fig. 10 showing retraction of a helical guide-channel.

Fig. 12 is a longitudinal section taken as on the line XII—XII of Fig. 1 looking in the opposite direction to Fig. 4.

Fig. 13 is a section taken on the line XIII—XIII of Fig. 12, showing the helical feed-in and cut-off mechanism, and switches.

Fig. 14 is an enlarged fragmentary view showing one of the cut-off switches.

Fig. 15 is a view of the helical coils looking in the direction of the arrow XV of Fig. 13.

Fig. 16 is an enlarged side elevation of the main timing cam and associated switch mechanisms.

Fig. 17 is a diagrammatic wiring diagram.

Referring now to the drawings in which the various parts are indicated by numerals:

The coils 10 which are to be secured together to form the spring assembly are of the usual hour glass form terminating in flat top and bottom heads 11 with the ends of the wire wrapped one or more times around the head convolutions forming completing knots 12 which are effective as positioning shoulders on these heads, the knot of the upper head being on the same side of the coil as the knot of the lower head. The heads also are crimped front and back to provide straight portions 13, 14 with end shoulders 15, which shoulders are adapted to pass through and lie between the turns of the helicals and restrict turning or shifting movement of the coil heads with respect to the helicals, the straight portions 13, 14 of the crimps being of unequal length to provide for their differing positions with reference to the helical turns and permit threading of smaller diameter helicals.

The machine includes a base 20, a top 21, and side walls 22, 23, connecting, and secured to the base and top forming a rectangular structure open both front and back.

Extending horizontally from side wall to side wall are four shafts 24, 25, 26 and 27 which are journaled in suitable bearings on these walls and which are provided with suitable collars preventing end thrust. Mounted on these shafts are groups of sprocket wheels in pairs, 30, 31; 32, 33; 34, 35; and 36, 37 respectively, these sprocket wheels being keyed to the shafts, preferably by keys 40, which engage keyways 41 extending substantially throughout the lengths of the shafts between bearings, each keyway and its related keys providing means to definitely align and coordinate the movement of all of the sprocket wheels on such shaft. The sprockets 30, 31 of shaft 24 respectively align along the shaft with the sprockets 32, 33 of shaft 25, the sprockets 34, 35 of shaft 26, and the sprockets 36, 37 of shaft 27.

All sprocket wheels have the same number of 75

flat faces, and teeth, preferably six. The sprockets 30, 32, and the sprockets 33, 34 carry upper and lower conveyor chains 42, 43 respectively, these chains having a pitch conforming to the faces of the wheels, and the remaining four sprockets of the group carry complementary upper and complementary lower chains 44, 45, the sprockets 30, 32 being respectively spaced along their shafts from the sprockets 33, 34 to align the conveyor chains 42, 43 with the side edges of the upper and lower heads 11, 12 of the coils to be handled, and the group spacings conforming to the desired longitudinal row spacing of the coils. The complementary chains each comprise link members 46 (Fig. 6 showing the lower set) coupled together by short side bars 47 and pins 48 of a standard form. The link members of one chain have arcuate grooves 49 conforming in arcuate radius to the radius of the top (or bottom) heads of the coils, the width and depth of the grooves conforming to the diameter of the wire of which the coil is formed. The link members of the complementary chain have similar arcuate grooves 50 which terminate adjacent the center of the member, at portions 51, which are of a depth substantially twice the wire diameter. These portions are shaped to receive the closing portion of the coil convolutions, and may be formed by cutting the top of the link away from the inner side leaving a shoulder 52 along the outer edge shaped to abut such closing portion. This wall is cut through at 53 to receive the knot 12. A pin 54 holds the coil portion A against the wall 52 and prevents shift of the coil along the groove. The top of the pin is beveled or shortened to permit coil portion 16 to clear.

The center portions of the member-linking bars 47 are of such depth relatively to link thickness that they do not extend above the bottoms of the pockets 51, and the end portions of the members 46 are beveled to provide approach slopes to this reduced depth.

The lower flights of the upper conveyors and the upper flights of the lower conveyors constitute the working portions of these structures, these upper and lower flights respectively underlying and overlying tables 55, and 56, respectively, against which the conveyor flights slide. These tables extend between and are rigidly secured at their ends to the side walls 22 and 23. Each table comprises two portions which are spaced apart to provide a slot which extends from side wall to side wall, these slots being adapted to receive helical guiding channel members 58, 59 respectively, hereinafter called helical guides, which are adapted to guide helicals 60, 61 across the machine. Secured on the tables on opposite sides of each of the conveyor flights are longitudinally disposed bars 62, 63 which form guide-ways for the flights, these bars likewise being interrupted for the helical guides.

The sprocket shaft 24 extends through the side wall 22 (Fig. 3) and has keyed thereon a ratchet wheel 64, which ratchet has the same number of teeth as the sprocket wheel has faces. The ratchet wheel is engaged by a pawl 65 carried by a swinging arm 66, which is connected by a link 67 to a crank pin 68 on a worm gear 69. The worm gear 69 is mounted on and keyed to a cam shaft 70 which extends transversely across the machine frame and is journaled in suitable bearings in the side walls 22 and 23. The worm gear is driven by a motor 71 as through pulleys 72, 73, a belt 74, shaft 75 and worm 76. The shaft 24, through spur gears 77

and idlers 18 drives the shaft 26 in opposite direction at the same speed.

The helical guides 58 and 59 comprise bars, designated by the same number, disposed transversely across the machine and having their respective upper and lower edges slidably disposed through the slots between the portions of the tables 55, and 56 respectively. These bars respectively have along their lower and upper edges channels 80, 81 conforming in width and depth to the diameter of the helical to be guided thereby. Preferably the bars are of a thickness slightly exceeding the diameter of the helicals and the channels are formed by placing side plates 82, 83 along the sides of the bars, these plates extending below or above the edges thereof, as the case may be, sufficient distances to provide the proper depth of channel. Disposed in the bottoms of the channels are pins 84 which are spaced at intervals conforming to the pitch of the helical to be used, and serve to longitudinally position the helical coils. The pins project from the bottoms of the channels slightly more than the diameter of the helical wire and serve to hold the straight portions 13, 14, of the coil crimps away from the channel bottom to permit threading through of the helicals. The facing edge portions of the helical guides 58, 59 including both bar and side plates 82, 83 are transversely notched to provide clearance openings 85 which allow the passage of the conveyor flight chains 42, 43; 44 and 45, and additionally the side plates 82, and 83 have shorter and shallower notches 86, 87 respectively (Figs. 6 and 9) which are adapted to receive and anchor the shoulders 15 of the coil head crimps.

Cooperating with the helical guides 58 and 59 are clamps 90 and 91 respectively which have arm portions 92, 93 hingedly connected as through brackets 94, 95 to the tables 55, 56 respectively. Each clamp 90 cooperates with the upper chain 44 for one longitudinal row of coils and the adjacent upper chain 42 for the next row of coils, and similarly the clamp 91 cooperates with the lower chains 45 and 43 for the same rows of coils. At the two opposite sides of the machine, halved clamps 90-A, 91-A; 90-B, 91-B are used.

Each of the clamps is transversely grooved in alignment with the helical guides to permit the helical guide complementary thereto, to extend beyond the surface of the chains and allow the clamp to lie flat both against the surface of the chains and the top of the guide. Each clamp when in closed position, as the clamp 91-C shown in Fig. 8, hold arcuate side portions of the abutting heads 11-A, 11-B of two coils of one longitudinal row, and arcuate side portions of the abutting heads 11-C, 11-D of two coils in an adjacent longitudinal row, solidly seated in the arcuate grooves of the links of the conveyor chains 43-A, 45-A respectively; hold down of the head portions 11-A, 11-B respectively holding the knots 12-A, 12-B of their heads in the wall cuts 53 of the links and the heads themselves against shifting, and definitely aligns and positions the straight portions 13, 14 of the crimps and the shoulders thereof in a complementary portion of the channel of the related helical guide. The clamp also closes the top of this channel and completes a square guideway through which the helical is to be threaded.

The helical guides 58, 59 are retractable (Fig. 11) so that they clear the facing surfaces of the tables 55 and 56 and permit free advance-

ment of the spring coils therealong. The helical guide 58 is urged toward retracted position by springs 96 and the helical guide 59 may similarly be so urged or may be allowed to drop by gravity.

5 97 are brackets which guide the sides of the helical guides 58 and 59 and if desired may limit the amount of their retraction. Contacting the outer edges of the helical guides are rollers 98 which are carried by arms 99, these arms being secured as by keys to shafts 100, 101 which are journalled in suitable bearings in the side walls 22, 23, these shafts projecting as through the side wall 22, and being linked together for co-ordinated oscillating movements in opposite directions by arms 102, and a link 103. Mounted on one of the shafts, as the shaft 101, and secured thereto is an arm 104, carrying at one end a roller 105 which rides on the face of a cam 106 which is keyed on the cam shaft 70 for 10 coordinated movement therewith. The cam 106 is adapted to hold the helical guides in guiding position during substantially one-half of a revolution of the cam shaft and to allow them to be retracted during the remaining portion of the 15 period.

20 The clamps 90 and 91 are adapted to be moved into helical guide engagement during the positioned period of the helical guides. The arms 92, 93 of these clamps are connected by links 107, 108, with arms 109, 110, which are mounted on and secured to shafts 111, 112, respectively, these shafts extending from side to side of the machine and being journalled in the side walls 22 and 23, both shafts extending through the wall 22 and being connected by arms 113, 114 and a link 115 for coordinated oscillation in opposite directions. One of the shafts, as the shaft 112, has secured thereon an arm 116 carrying a roller 117, which rolls on the face of a cam 118 secured on the cam shaft 70, this cam having a face portion adapted to hold the clamps in closed position during substantially half the cam revolution and an additional portion adapted to allow retraction of the clamps during the remaining portion of the period. The clamps are urged 25 towards open position as by springs 119.

30 Disposed adjacent corresponding ends of the helical guides 58, 59 and carried by the table 56 and side wall 22 are tilting type mercury switches 120, 121, the switch 121 (Fig. 10) having a cam plate 122 adapted for displacement by end thrust of the helical 61 and the switch 120 having a similar cam plate 123 displaceable by end thrust of the helical 60.

35 55 Mounted on the opposite side wall 23 and aligned with the opposite ends of the channels 58, 59 are guide tubes 125, 126. Alined with the tubes 125, 126 are helical forming heads 127, 128 of a well known type forming part of a helical forming and threading machine 129 which is secured to the wall 23 of the machine.

40 60 65 Wires 130, 131 are forced by pairs of rolls 132, 133 respectively through the forming heads 127, 128 and emerge in well known manner as the spirally advancing helicals 60, 61. The rolls 132 and 133 are driven through suitable shafts and gearing and respectively related clutches 134 and 135 and a sprocket chain 136 by a motor 137. The clutches 134 and 135 are respectively engaged by energization of solenoids 138 and 139 biased to hold the clutches open.

45 50 55 60 65 70 Disposed between the inner ends of the tubes 125 and 126 and the ends of the helical guides 58, 59 is a helical cut-off which is adapted to sever the helicals 60, 61 after they have been threaded

through the machine and have respectively joined together the upper and lower heads of abutting coils. This cut-off includes upper and lower frame members 140, 141 which are respectively secured to the tables 55 and 56. These frame members respectively have passageways therethrough for the helicals 60 and 61. Each frame member carries a fixed cut-off knife, as the knife 142, of the frame member 140, these knives being substantially united and projecting downward with their cutting edges adjacent the bottoms of the helicals, as the helical 60, which is shown threaded therewith. Slidably mounted in the frame members is a vertically disposed cutter bar 143 which carries identical movable knives 144, 145 which are adapted to cooperate with the fixed knives, as the knife 144 with the knife 142, and cut off the helicals when the bar 143, and the movable knives carried thereby, is raised. The cutter bar 143 extends above the frame 140 and is pinned secured to an arm 146 (Fig. 2), one end of the arm being supported by a thrust member 147 connected as by pins 148, 149 to the frame 140 and arm 146 respectively. The free end of the arm 146 is connected as by a link 150 to the plunger 151 of a solenoid 152, energization of the solenoid raising the end of the arm 146 and through this arm raising the bar 143 and the knives 144 and 145 carried thereby. Retraction of the arm is accomplished by a spring 153.

Figs. 2 and 16 show a timing cam 160 mounted on the shaft 70, a casing 161, housing a switch which makes and breaks a circuit controlling the starting and stopping of the helical forming and feeding mechanism; a casing 162 housing a switch making and breaking the helical cut-off circuit, and a casing 163 housing a switch which makes and breaks an auxiliary circuit to the motor 71, these switches being designated in Fig. 17 by these casing members. 164 is an arm carrying a roller 165 riding on the face of the cam 160 through which the switch 161 is closed when the roller rides outward at the rise 160-A of the cam and is opened when the roller moves inward at the fall 160-B of the cam, the switch being closed between the rise and fall and open between the fall and rise, each period being approximately one-half the turn of the cam. The switch 163 is provided with a similar arm 166 and roller 167 which similarly actuates the switch 163. The switch 162 has a similar arm 168 and roller 169. This arm, however, is actuated by a pin 170 which momentarily shifts the roller 169 outward to close the switch 162 and actuate the helical cut-off knives, and thereafter lets it drop inward to again open the switch and break the circuit. All of the switches 161, 162 and 163 are biased open.

The circuits for the motor 71, the solenoids 152 which actuate the cut-off mechanism and the solenoids 138 and 139 which actuate the helical feed is shown in Fig. 17. 175 is the line switch through which the motor 71 is started and 176 an emergency switch through which the operator can kill the motor circuit in emergency, or otherwise. 177 is a main lead from switch 175 through branch lead 177-A to motor 71; 177-B, 177-C to helical actuating solenoids 138 and 139; 177-D to helical cut-off solenoids 152; and 177-E, 177-F to relays 178, and 179, which actuate double throw switches 180, 181, having each two sets of contacts. The solenoids 138, 139 are connected through parallel return leads 182, 183 respectively with the A contacts of switches 180, 181, and thence through joint return leads 184, 185 to the power switch 175. The B contacts of 180, 181 are interposed in series in the return lead 186-A, B, C, and D and leads 184, 185 to the switch 175.

Circuits through relays 178, 179 are respectively completed by parallel leads 187, 188 through switches 121, 120, through a joint lead 190, switch 161 and lead 185 to the power switch return lead 190. The solenoids 152 include switch 162 and is completed through leads 184, 185. An auxiliary return lead for the motor 71 includes the return leads 186, 186-A, lead 191, the switch 163 and the return leads 184, 185.

In starting operation, the line switch 175 is closed energizing and starting the motor 71 and tending to establish circuits to the helical feeding solenoids 138, 139 and the helical cut-off solenoid 152. The motor 71 through the belt driven worm 76 turns the gear 69 in the direction of the arrows shown thereon in Fig. 3, and drives the cam shaft 70 in the same direction. Through the link 67 and arm 66 the pin 68 on the gear 69 advances and retracts the pawl 65 advancing the ratchet wheel 64 during the advance half of the stroke but leaving it stationary during the return stroke. Movement of the ratchet wheel 64 similarly turns the shaft 24 and through the idler gears 78 oppositely turns the shaft 26, these shafts respectively correspondingly moving the groups of sprocket wheels 30, 31; 34, 35; and corresponding groups of conveyor chains 42, 43; 44, 45; the conveyor chains advancing during the forward half stroke and remaining motionless during the pawl retraction half stroke.

During a stationary or dwell period all the coils 10 needed to make up a transverse row of coils of the spring assembly are placed in the transversely aligned row of links lying between the shafts 25 and 27. The side edges of the top and bottom heads 11 being seated in the grooves 49, 50 of the conveyor chain links with the positioning knots 12 in the link pockets formed therefor and against the pins 54, this definitely positioning the straight forward and rearward portions 12, 14 of the head crimps, and this regardless of any twist initially of one head in regard to the other. During the succeeding half turn this row of coils is advanced one link space and a second row placed during the next dwell period of a cycle. As the fifth row of coils is being placed the rear edge portions 14 of the top and bottom heads of the first placed row of coils and the lapping forward edge portions 13 of the next placed row of coils are aligned with the helical guides 58 and 59.

As the edge portions of the coil heads approach alignment with the helical guides 58, 59 the rise portion of the cam 160 engages the roller 105, and through the connected linkages depress and raise the helical guides 58, 59 respectively, into such position that the overlapping head crimp portions 13, 14 lie in the helical channels and against the pins 84 of such channels. At the same time the approach portion of the cam 118 engages the roller 117 and through the interconnected linkage moves the clamps into position against the open helical channels and also into position to solidly hold side portions of the coil heads in the grooves of the chains, and the crimps in the helical channels.

Shortly after the motor 71 is started the motor 137 which drives the helical formers is also started. As the helical channels and clamps are moved into operative position by their respective cams, the cam 160 on the same cam shaft is timed to advance its approach portion 160-A in-

to engagement with the roller 165 of switch 161 closing this switch, as shown in Fig. 17, and establishing circuits through leads 177-A, 177-E, relay 178, leads 188 and switch 120 to joint lead 190, and through leads 177-A, 177-E, 177-F, relay 179, lead 187, switch 121 and lead 181-A to joint lead 190, thence through switch 161 and lead 185, energizing these relays and bridging the A contacts of the switches 180 and 181. The circuits completed through these switches, solenoid 138, leads 177-B, 182, 184 and 185, and solenoid 139, leads 177-C, 183, 184, and 185, energizes these solenoids, and through the clutches 134 and 135 couples the motor 137 to drive the feed rolls 132, 133 of the helical coiler. These rolls feed the wires 130, 131 through the coiler heads 127, 128 and advance the helicals formed thereby with a spiral rotary motion through the tubes 125, 126, the channelways in the cut-off frames 140, 141 and the helical channels 58, 59 to couple the crimps of top and bottom heads of the two abutting coils together. In the spiral advancement of the helicals through the channels the pins 84 definitely position the helicals longitudinally of the channels, these pins being so positioned relatively to the crimp portions 13, 14 that the helical will first enter the longer underlying crimp portion, as in Fig. 8, and then the shorter overlying crimp 13, and in leaving the crimp will first leave the shorter and then the longer crimp. The helicals are advanced entirely across and connect an entire transverse row of abutting coil heads during a stoppage of the chain links. As the helicals emerge from the last row of coils and the ends of the helical channels, they engage the cam edges 122, 123 of the switches 120, 121, tilting these switches into off position and breaking the circuit through these switches to the relays 178, 179, thus releasing the switches 180, 181 from the contacts A thereof, de-energizing solenoids 138, 139, and stopping the formation and advancement of the helicals. Subsequent to this stoppage the pin 170 engages the roller 169 and closes switch 162, energizing solenoid 152. This solenoid through arm 146 raises the cut-off bar 143 and the knives 144, 145 carried thereby and cuts both helicals 60 and 61.

Shortly before cut off of the helicals the roller 165 reaches the cam drop 160-B and the switch 161 is opened breaking the circuit to the mercury switches 120, 121 and the relays 178, 179 and allowing the switches 180, 181 to bridge their B contacts and reestablish the motor circuit through such contacts. During the stoppage period of the conveyors a succeeding transverse row of coils is placed in the conveyors.

Immediately following the helical cut off, cam 106 releases the helical channels 58 and 59 and permits their retraction and cam 118 similarly releases the clamps 90, 91 and allows them to open. The gear 60, through pin 68, link 67 and pawl 65 begins advancement of the coils to new position. As this shift begins the helicals are shifted from beneath the cams 123, 122 of the switches 120, 121 and these switches again close reenergizing the relays 178, 179 and tending to re-energize the solenoids 138 and 139 of the helical feed roll clutches.

During the operating cycle, as the cam 160 turns, the roller 167 is raised by the approach 160-A of the cam, closing the switch 163 and establishing during about one-half cycle a motor circuit through leads 177, 177-A; 186, 186-A, this circuit being established before the switch 75

161 is closed and the circuit through the B contacts of switches 180, 181 is broken by the energization of the relays, and the two circuits establishing continuous power to the motor during normal operation.

Should one of the helicals be slightly slower in reaching the switches 120, or 121, the circuit through switch 163 will carry over even though one relay be energized and the circuit through the switch 161 be broken. If, however, both helicals do not reach the switches 120, 121 before the roller 167 drops and opens the switch 163, both circuits would be broken and stoppage of driving motor 71 occurs until the delayed helical reaches its cut off switch and reestablishes the motor circuit through leads 186-B, C and D. If helical delay persists, the main switch 175 is cut off until the trouble can be corrected.

It will be understood that in engaging the coils, by hand, in the conveyor links, the bottom head of each coil is seated in the chain grooves of links of the lower flight, with the front crimp overlying the rear crimp of the lower coil head immediately forward thereof, the coil is then compressed ordinarily about one inch in length and the upper head is engaged in the chain grooves of the upper flight, with its forward crimp underlying the rear crimp of the upper coil head immediately forward, the coil thus placed holding solidly by reason of such compression.

It will be understood that the present machine is designed for thus overlapping the coil crimps in order that minor inequalities in the distances between crimps in any coil or coils may not defeat abutment of the crimps, a crimp spacing even a wire diameter in excess or short still making abutting engagement. The abutment however may be edge to edge rather than overlapping should it be deemed more satisfactory.

40 In beginning a spring assembly helicals are run through top and bottom along the forward crimps of the first row of coils finishing the first or forward edge of the assembly. When the full number of rows of coils for an assembly has been placed, a row of coils is omitted and subsequently helicals are fed through along the rear crimps, top and bottom, of the last row of coils of the assembly completing the rear edge of such assembly, and the helicals next placed complete the forward edge of the next spring assembly.

I claim:

1. Spring assembling mechanism including a plurality of substantially identical units, movably disposed along adjacent parallel paths, each said unit including an opposed pair of carriers means for holding a plurality of springs with edge portions of their opposed heads in respective abutting relation; means coordinating the positioning of said carriers along said paths to aline the abutting head portions of said springs in transverse rows and for advancing said carriers concurrently step by step an even head spacing, with dwell periods between said steps; and means alined with one position of abutting head advancement coordinated to operate during said dwell period to spirally advance helicals across all of said paths and in wrapping engagement with said alined abutting head portions.

2. Spring assembling mechanism including a plurality of substantially identical units movably disposed along adjacent parallel paths, each said unit including a spaced pair of carriers means for holding a plurality of springs with edge portions of their opposite heads in respec-

tive abutting relation; means coordinating the positioning of said carriers along said paths to aline the abutting head portions of said springs in transverse rows and for advancing said carriers concurrently step by step an even head spacing, with dwell periods between said steps; means, alined with one position of abutting head advancement and coordinated to operate during said dwell period, for spirally advancing helicals across said paths and in wrapping engagement with said alined abutting upper and lower head portions respectively, means for independently stopping advancement of said helicals and means for cutting off said helicals.

3. Spring assembling mechanism including a plurality of substantially identical units movably disposed along adjacent parallel paths, each said unit including a spaced pair of carriers means for holding a plurality of springs with edge portions of their opposite heads in respective abutting relation; means coordinating the positioning of said carriers along said paths to aline the abutting head portions of said springs in transverse rows and for advancing said carriers concurrently step by step an even head spacing, with dwell periods between said steps; means, alined with one position of abutting head advancement and coordinated to operate during said dwell period, for spirally advancing helicals across said paths and in wrapping engagement with said alined abutting upper and lower head portions respectively, and means for cutting off said helicals.

4. Spring assembling mechanism including a plurality of substantially identical units movably disposed along adjacent parallel paths, each said unit including a spaced pair of carriers means for holding a plurality of spring coils in respective upright positions with edge portions of their upper and lower heads in abutting relation; means, coordinating the positioning of said carriers along said paths to aline the abutting head portions of said coils in transverse rows, and for advancing said carriers concurrently step by step an even head spacing, with dwell periods between said steps; channel shaped helical guides, alined with one position of abutting head advancement and extending transversely across said paths, means, coordinated to operate during said dwell period, for raising and lowering said guides respectively into adjacency with the sides, and bottom and top respectively of said lower and upper head edge portions respectively, and means spirally advancing helicals through said channels and in wrapping engagement with said head portions therein, said raising and lowering means being adapted to reversely lower and raise said guides out of the path of advancement of said head portions subsequent to advancement of said helicals therethrough.

5. Spring assembling mechanism including a plurality of substantially identical spring carriers movably disposed along adjacent parallel paths, each said carrier including means for holding a plurality of spring coils in upright positions with edge portions of their upper and lower heads in abutting relation; means, coordinating the positioning of said carriers along said paths to aline the abutting head portions of said coils in transverse rows, and for advancing said carriers concurrently step by step an even head spacing, with dwell periods between said steps, channel shaped helical guides, alined with one position of abutting head advancement and extending transversely across said paths, means, coordinated to

operate during said dwell period, for raising and lowering said guides respectively into adjacency with the sides, and bottom and top respectively of said lower and upper head portions respectively, means coordinated to operate during said dwell period to clamp side portions of said coil heads in said carriers, and means spirally advancing helicals through said channels and in wrapping engagement with the head portions therein, said raising and lowering means being actuated to reversely lower and raise said guides out of the path of advancement of said head portions, and said clamps to release said coil heads, subsequent to advancement of said helicals therethrough.

6. Assembling mechanism for coil springs, having tie knots and crimped heads with straight crimp portions, including a plurality of carriers movably disposed along adjacent parallel paths, each said carrier including four conveyor chains in pairs, spaced laterally apart to receive side portions of the heads of said coils, the upper and lower chain of each pair having facing flights spaced apart to receive said coils, said chains having a pitch corresponding to the distance from crimp to crimp of said coils, the facing portions of the chain links being grooved to embed side portions of the heads of said coils, the links on one side additionally each having a pocket chambered out to receive and position a said knot, and thereby position its said head definitely with relation to said links, said pockets being positioned to aline the straight portions of said crimps at right angles to the line of said chains and in abutting relation to the crimps of adjacent chains.

7. Assembling mechanism for coil springs, having tie knots and crimped head portions, including a plurality of carriers movably disposed along adjacent parallel paths, each said carrier including four conveyor chains in pairs, spaced laterally apart to receive side portions of the heads of said coils, the upper and lower chain of each pair having facing flights spaced apart to receive said coils, said chains having a pitch corresponding to the distance from crimp to crimp of said coils, the facing portions of the chain links being grooved to embed side portions of the heads of said coils, the links on one side additionally each having a pocket chambered out to receive and position a said knot, and thereby position its said heads definitely with relation to said links, said pockets being positioned to aline the straight portions of said crimps at right angles to the line of said chains and in abutting relation to the crimps of adjacent chains, and means to transversely aline the links of the chains of said carriers and to coordinate the movement thereof.

8. Assembling mechanism for coil springs, having tie knots and crimped heads with straight crimp portions, including a plurality of carriers movably disposed along adjacent parallel paths, each said carrier including four conveyor chains in pairs, spaced laterally apart to receive side portions of the heads of said coils, the upper and lower chain of each pair having facing flights spaced apart to receive said coils, said chains having a pitch corresponding to the distance from crimp to crimp of said coils, the facing portions of the chain links being grooved to embed side portions of the heads of said coils, the links on one side additionally each having a pocket chambered out to receive and position a said knot, and thereby position its said head definitely with relation to said links, said pockets being posi-

tioned to aline the straight portions of said crimps at right angles to the line of said chains and in abutting relation to the crimps of adjacent chains, means to synchronize the alinement transversely of the links of said carriers, and the movement thereof, means to advance said carriers with a link by link movement and to alternate such movements with dwell periods, upper and lower helical guides in alinement with a position of advancement of each said pair of abutting coil crimps in succession; and means synchronized for action during said dwell period, respectively for lowering and raising said helical guides respectively into housing position with relation to said crimps, for clamping said coil heads in said links on adjacent opposite sides of said guides, for spirally advancing helicals through said guides in wrapping engagement with said crimps, for retracting said guides and for releasing said clamps.

9. In a machine for assembling and connecting parallel rows of coil springs, the combination of a frame structure, spaced bed and top plates mounted on said frame structure, means on the opposed faces of said plates for guiding rows of springs inserted between said plates, guide channels, adapted to embrace adjacent portions of the end coils of adjacent rows, disposed adjacent and crosswise of said spring guiding means, means for moving said guide channels into embracing position, means for feeding wire helicals endwise through said channels and simultaneously rotating said helicals on their axes, means associated with said channels for guiding the coils of said helicals around the adjacent portions of said end coils, and means for removing said channels after said helical feeding therethrough.

10. In a machine for assembling and connecting parallel rows of coil springs, the combination of a frame structure spaced bed and top plates mounted on said frame structure, means on the opposed faces of said plates for guiding rows of springs inserted between said plates, guide channels, adapted to receive adjacent portions of the end coils of adjacent rows, disposed in adjacency and crosswise of said spring guiding means, means for feeding wire helicals endwise through said channels and simultaneously rotating said helicals on their axes, means associated with said channels for guiding the coils of said helicals around the adjacent portions of said end coils, and means for advancing said channels into guiding position prior to helical feed advancement and for retracting said channels subsequent to completion of such advancement.

11. In a machine for assembling and connecting parallel rows of coil springs, the combination of a frame structure, spaced bed and top plates mounted on said frame structure, means on the opposed faces of said plates for guiding rows of springs inserted between said plates, guide channels adapted to embrace adjacent portions of the end coils of adjacent rows, means for feeding wire helicals endwise through said channels and simultaneously rotating said helicals on their axes, means associated with said channels for guiding the coils of said helicals around the adjacent portions of said end coils, means for advancing said channels into embracing position, subsequent to such feeding, out of the path of said helicals and the portions of said end coils connected thereby and means for shifting the connected rows of springs laterally past said retracted channels.

12. In a machine for assembling and connect-

ing parallel rows of coil springs, the combination of a frame structure, spaced bed and top plates mounted on said frame structure, means on the opposed faces of said plates for guiding rows of springs inserted between said plates, guide channels, adapted to embrace adjacent portions of the end coils of adjacent rows, disposed transversely to but out of the path of advancement of said coils, means for advancing said channels into embracing position, means for feeding wire helicals endwise through said channels and simultaneously rotating said helicals on their axes, means associated with said channels for guiding the coils of said helicals around the adjacent portions of said end coils, means for retracting said channels out of the path of said helicals and the portions of said end coils connected thereby, means for shifting the connected rows of springs laterally of said channel, and for advancing another row of springs for connection in the same manner to one of said previously connected rows of springs.

13. Spring assembling mechanism of the character described, comprising in combination means for supporting two parallel rows of coil springs with coil heads of one said row in respective abutting adjacency with corresponding heads of the other said row; means for shifting said rows in said relation to bring said abutting head rows respectively each into and out of helical path alinement, means for feeding wire helices respectively endwise along said paths and simultaneously rotating said helices on their axes, means for guiding said helices so as to cause the coils thereof respectively to be wrapped around the respective abutting portions of said heads, and means for shifting said guiding means into and out of the path of said row advancements respectively prior and subsequent to said helical feeding.

14. In a machine for assembling and connecting parallel rows of coil springs, which includes means for advancing parallel rows of springs in abutting relation with a step by step motion with interposed dwell periods, an electric motor for driving said machine; and electrically responsive means for concurrently advancing helicals in pairs for respectively connecting said coils; energized circuits comprising, a first motor circuit including a switch biased open, a second motor circuit by-passing said switch and including in series a pair of switches biased closed, a pair of solenoids connected respectively to said switches and adapted on energization to open same, a pair of third circuits in parallel including respectively each a said switch biased open and adapted for closure by a said solenoid, said circuits leading respectively each to a said helical advancing means, and a pair of fourth circuits, having a joint lead including a closure switch biased open, and leading in parallel respectively through said solenoids, said fourth circuits including each a trip switch biased closed, said trip switches respectively being positioned and adapted for opening by completion of respective helical advancements; and a timing cam driven by said motor and coordinated with said step by step movement of said machine, said cam having a switch closing portion and a switch release portion, each of substantially 180 degrees, said first circuit switch and said fourth circuit closure switch being positioned respectively for successive opening and successive closing, with said fourth circuit closure timed to occur shortly subsequent to the beginning of said dwell period.

15. A mechanism in accordance with claim 14 including a helical cut-off mechanism, adapted to cut off said helicals, an actuating solenoid for such cut-off, a circuit, including a switch biased open, leading through said solenoid, and means carried by said timing cam, for closing said switch momentarily, said switch being positioned for actuation by said cam immediately subsequent to cessation of helical advancement.

16. In a machine for assembling and connecting parallel rows of coil springs, which includes means for advancing parallel rows of springs in abutting relation with a step by step motion with interposed dwell periods, an electric motor for driving said machine; and electrically responsive means for concurrently advancing helicals in pairs for respectively connecting said coils; energized circuits comprising, a first motor circuit including a switch biased open, a second motor circuit by-passing said switch and including in series a pair of switches biased closed and a pair of second electrically responsive means connected respectively to said switches and adapted on energization to open same, a pair of third circuits

in parallel including respectively each a said switch biased open and adapted for closure by a said second electrically responsive means, said circuits leading respectively each to a said helical advancing means, and a pair of fourth circuits, having a joint lead, including a closure switch biased open, and leading in parallel respectively through said second electrically responsive means, said fourth circuits including each a trip switch biased closed, said trip switches respectively being positioned and adapted for opening by completion of respective helical advancements; and a timing cam driven by said motor and co-ordinated with said step by step movement of said machine, said cam having a switch closing portion and a switch release portion each of substantially 180 degrees, said first circuit switch and said fourth circuit closure switch being positioned respectively for successive opening and successive closing, with said fourth circuit closure switch timed to occur shortly subsequent to the beginning of said dwell period.

JONATHAN A. DICKEY.
